ABSTRACT

A mop head holder adapted for removable attachment to a retaining clip of a mop handle and being particularly designed for the reception and support of a wet-type mop head.

MOP HEAD HOLDER

This invention relates to mops, and more particularly to means for removably securing a replaceable mop head on a mop handle.

In the use of mops to clean floors, particularly in commercial and industrial establishments, it is a common practice to provide means for removably replacing the mop heads on their support handles. This not only facilitates periodic cleaning of the mop heads for use, but also permits the use of different types of mop heads with a common support handle. Generally, the means for removably attaching such mop heads to the support handle comprises a receiving member, such as a clip, which may be permanently or removably attached to the end of the mop handle, and a mop head holder, such as a wire frame or the like which directly contains and supports the mop head and is removably secured to the mop handle by the clip.

Typical of such mops of the type described is that disclosed in previously issued U.S. Pat. No. 3,029,454 which describes a mop composed of a mop handle and retaining clip attached thereto for removably receiving and supporting a mop head of the dry, or dust mop type. As shown in the drawings of the patent, the mop head 6 itself is removably supported on an elongate wire frame 13 which has an inner frame portion 18 pivotally removably attached to a clip member 27 secured to the end of a mop handle 26. The clip 27 is composed of two plates 28, 41 which are pivotally attached and spring-biased to grippingly receive a cross-rod 25 (FIG. 2) of the mop head support frame 13 to pivotally support same during use.

Particularly in industrial and commercial use, it is desirable to employ both dry mops of the type described in the foregoing patent and wet mops, typical of which is described in U.S. Pat. No. 2,492,232. The heads of such wet mops generally are constructed of a plurality of elongate generally parallel strings or threads which are attached at their midpoint to a suitable support bracket or rod for use. From a standpoint of economy as well as improved storage and use, it is desirable to provide a mop tool having the capability of alternately supporting on a common handle both dry and wet mop heads of the type described.

It is therefore an object of the present invention to provide a mop head holder for a wet mop of the type described which may be readily removably attached to and used with a mop tool having the clip-type securing member also utilized to support a dry mop head as described in U.S. Pat. No. 3,029,454.

The foregoing as well as other objects of the present invention may be best understood and explained by reference to the accompanying drawings in which

FIG. 1 is a perspective view of a wet mop including a handle, mop head, and retaining means for removably supporting the mop head on the handle embodying features of the present invention;

FIG. 2 is an enlarged fragmentary perspective view of the mop head retaining section of the mop of FIG. 1, with the mop head holder shown removed from the clip retainer for better clarity;

FIGS. 3A and 3B are enlarged front and plan views, respectively, of the mop head holder of FIG. 2; and

FIG. 4 is a sectional view of the mop head retaining section taken generally along line 4-4 of FIG. 1, and with the mop head removed for convenience.

Referring now more specifically to the drawings, FIG. 1 shows a wet mop including a portion of a handle 10 to which is attached a retaining clip 12 which removably supports a mop head holder 14 and a mop head 16. Mop head 16 is composed of a plurality of strings or threads 18 which are disposed in generally parallel side-by-side relation and are sewn together at the approximate midpoint of their length with a fabric binder 20. Such a mop head construction is typical of the wet mop head types that are removably attachable to mop tools for commercial use.

As best seen in FIGS. 2 and 4, the retaining clip 12 is composed of a first plate 22 pivotally attached by a bolt or rivet 23 to an upwardly extending flat shaft 24. Shaft 24 is secured to the end of mop handle 10 by an attaching sleeve 26 and rivet

28. A second plate 30 is pivotally secured to the first plate 22 by a pivot pin 32 which extends through aligned openings of a pair of projecting fingers 34, 35 on each of the plates and the lower ends of plates 22 and 30 are urged into contact by a coiled spring 36 surrounding pivot pin 32. Secured to the inside face of plate 22 by rivet 23 is a rigid third plate 37 having a pair of spaced, downwardly projecting ears 38, 40 which are positioned at the opposite outer edges of the second plate 30 (FIG. 2). Ears 38, 40 are spaced outwardly from the bottom portion of first plate 22 to form a space therebetween for the reception of a portion of the mop head holder which will be described.

The upper portion of first plate 22 has a tongue portion 42 which extends along the face of shaft 24. The sides of the tongue portion 42 are releasably engaged by C-shaped clamp 44 which is slidable on shaft 24 to release clip 12 for pivotal movement about rivet 23, thus permitting greater maneuverability of the mop head holder and mop head on the mop handle. The position of clamp 44 on shaft 24 is controlled by a leaf spring 46 (FIG. 4).

Mop head holder 14 of the present invention is best shown in FIGS. 2 and 3 and is composed of a relatively rigid, loop-shaped rod 50 having end portions 52, 54 extending in generally parallel spaced side-by-side relation. Finger-like elements 56, 58 are suitably attached to rod end portions 52, 54, respectively, as by welding, and have inwardly projecting sections 56a, 58a, respectively, which extend towards each other in opposing relation and lie in a common plane which is spaced from and parallel to the plane of the rod end portions 52, 54. Sections 56a, 58a and end portions 52, 54 of the rod 50 define between them a space for the reception of first plate 22 of the clip. The faces of the rod end portions 52, 54 opposing the finger-like elements may be suitably flattened, as shown, to facilitate the reception of flat plate 22.

As shown in FIGS. 1 and 4, finger-like elements 56, 58 are slidably received in the opening between projecting ears 38, 40 and the lower end of first plate 22, while the crimped lower end portion of second plate 30 underlies and engages the finger-like elements 56, 58 of the mop head holder 14 to firmly secure the same to the clip 12 during use.

As best seen in FIG. 1, the central fabric-bound portion of mop head 16 is retained within the loop portion of the mop head holder 14 during use. Mop head 16 may be readily inserted within the loop portion when the holder 14 is removed from the clip by passing the center portion of the mop head between the rod end portions 52, 54 and the end portions of the finger-like elements 56, 58 which terminate a sufficient distance apart to permit easy passage of the mop head therebetween for retention within the loop of the rod.

From the foregoing description, it can be seen that the mop head holder of the present invention may be readily employed with the mop tool clip member of the type normally used to support dry mop frames so as to permit the use of a single mop handle for the support of both wet and dry mops of the type described.

That which is claimed is:

1. A mop head holder adapted for removable attachment to a retaining clip of a mop handle to support a mop head thereon, comprising a relatively rigid, loop-shaped rod having end portions extending in generally parallel, spaced side-by-side relation, a relatively rigid finger-like element attached to each of said rod end portions and having a section extending inwardly between said rod end portions, said sections extending in opposing relation to each other and in a plane parallel to a plane extending through the rod end portions, adjacent ends of said sections terminating a sufficient distance apart to permit passage of a portion of a mop head therebetween for its placement and retention within the loop of said rod, and a retaining clip having a first plate portion slidably received between said finger-like elements and said end portions of said rod and being engaged thereby, a pair of projecting ears attached to and spaced from said plate for slidably receiving said finger-like elements therebetween, and a spring-biased second

plate pivotally attached to said first plate and having an end portion in overlying engagement with said finger-like elements cooperating with said ears and said first plate to removably secure said mop head holder in said clip.

2. A mop head holder adapted for removable attachment to a retaining clip of a mop handle to support a mop head thereon, comprising a relatively rigid rod defining a generally oval loop of unrestricted interior for the reception and support of a mop head therewithin, end portions of said rod extending in generally parallel, spaced side-by-side relation, means attached to each of said rod end portions and extending toward each other in a common plane spaced from the plane extending through said rod end portions to define a passage between said means and said rod end portions for the reception and en-

gagement of a portion of a retaining clip therebetween to facilitate securement of the holder on a mop handle, and adjacent ends of said inwardly extending means terminating a sufficient distance apart to permit the passage of a portion of the mop head therebetween for its placement within the loop of the rod.

3. A mop head holder as defined in claim 2 wherein said inwardly extending means comprises a relatively rigid finger-like element attached to each of said rod end portions and having a section thereof extending inwardly between said rod end portions, and said sections extending in opposing relation to each other and in a plane parallel to a plane extending through the rod end portions.
